US00D400180S

United States Patent [19]

Shimizu

[11] Patent Number: Des. 400,180

[45] Date of Patent: **Oct. 27, 1998

[54] PROGRAMMABLE LOGIC CONTROLLER

[75] Inventor: Norio Shimizu, Tokyo, Japan

[73] Assignee: Facts Engineering, Inc., New Port Richey, Fla.

[**] Term: 14 Years

[21] Appl. No.: 59,404

[22] Filed: Sep. 10, 1996

[30] Foreign Application Priority Data

May 30, 1996 [JP] Japan 8-15509

[51] LOC (6) Cl. 13-03

[52] U.S. Cl. D13/162.1

[58] Field of Search D13/162.1; 361/686, 361/752, 600, 601, 627, 641

[57] CLAIM

The ornamental design for a programmable logic controller, as shown and described.

DESCRIPTION

FIG. 1 is a front view of the controller incorporating my new design;

FIG. 2 is a top view;

FIG. 3 is a rear view;

FIG. 4 is a right side view;

FIG. 5 is a left side view;

FIG. 6 is a bottom view; and,

FIG. 7 is a perspective view of the controller of FIG. 1 viewed from the lower right hand corner.
